UNITED STATES PATENT OFFICE

2,478,236

CHILD'S CHAIR

Homer Carr, Hollywood, Calif.

Application May 7, 1945, Serial No. 592,319

1 Claim. (Cl. 155—191)

1

This invention relates to furniture specially adapted for the use of infants and small children and has for its object to provide a very comfortable, durable and at the same time very inexpensive chair.

Another object of the invention is to provide a chair in which an infant may be seated and secured without danger of its falling therefrom.

A further object of this invention is to provide a chair with a cushion support, whereby it may be set upon a highly polished floor, table or other base without possibility of scratching the same.

A still further object of the invention is to provide in an infant's chair integrally formed strap supporting means.

Other features and advantages will become more readily apparent from the following description and the accompanying illustrative drawings in which:

Figure 1 is a front elevational view of my improved chair,

Figure 2 is a sectional view taken on line 2—2 thereof,

Figure 3 is an elevational view of the chair taken from the back,

Figure 4 is a section on line 4—4 of Figure 1, and

Figure 5 is an enlarged detail of a strap end.

In the accompanying drawings as above enumerated and in the following specification, like characters of reference indicate like parts throughout and in which 10, indicates my improved infant's chair which consists of a seat 11, the rear peripheral edge 12, of which is semi-cylindrical. To this edge is attached an oval shaped member 13, which forms the back 14, side wings 15 and 16, and a support 17, for the rear of the chair. The front and free edge 18, of the seat 11, is slightly arcuate and has depending therefrom an apron 19, which reaches from wing to wing. The lower edge 20, of said apron is provided with a reinforcing strip 21, which also acts to bind an elongated cushion 22, to said edge. A similar strip 23, is provided on the rear lower edge 24, of the back 14, and also binds a similar cushion 25. These cushion members may be formed of felt padding, solid rubber, inflated tubing, or the like.

Adjacent the back 14, are provided oppositely disposed pairs of slots 26 and 27, each fair forming a buckle means for locking the ends 28 and 29, of a strap 30, therein. This strap is intended to be passed around the chest of an infant, under its arms in order to prevent it from falling forward in the chair. Similar sets of slots 31 and

2

32, are provided in the wings 15 and 16, adjacent the outer edges 33 and 34, to hold the ends 35 and 36, of a strap 37, as a secondary precautionary means for holding an infant, or for the use on an older child. These slots are enlarged at the upper ends 38, and reduced at the lower portions 39, in order that the strap ends may be easily passed through the enlarged portions and then shoved down to wedge in said lower portions. In Figure 5, it will be noted that the end 40, of strap 41, is enlarged to pass through an upper slot 38, and when pushed down into the lower slot 39, it will be secured therein. This strap is slightly shorter than the distance between slots 32 and 33, but the wings 15 and 16, are sufficiently flexible to permit them being pressed toward one another to permit the end 42, to pass through an opposite slot after the end 40, has already been secured, thus the strap will be held taut across the chair. A hand hole 43, is provided adjacent the upper edge 44, of the back 14.

The above described chair may be formed entirely of plywood, sheet metal or other suitable light material, and aside from the cushions and straps, may be made complete with only three pieces of material. A bore 45, may be provided in the center of the back 14, just under the seat 11, for a rope and screw eyes 46 and 47, provided adjacent the opposite outer edges 48 and 49, of the bottom 50, of said seat and at the spaces 51 and 52, between the opposing edges 53 and 54, and 55 and 56, of members 13 and 19, to which ropes may be attached for suspending the chair in an automobile or elsewhere.

35 It is thought that persons skilled in the art to which the invention relates will be able to obtain a clear understanding of the invention after considering the description in connection with the drawings. Therefore, a more lengthy description is regarded as unnecessary.

40 Minor changes in shape, size and rearrangement of details and parts such as come within the purview of the invention claimed may be resorted to, in actual practice, if desired.

45 Having now described my invention, that which I claim as new and desire to procure by Letters Patent is:

50 A chair having a substantially semi-circular seat, a substantially oval-shaped flexible member attached to an edge thereof forming an integral back, side arms and rear support for the seat, a depending arcuate apron secured to the front edge of the seat forming a front support, said side arms being formed with transversely and vertically spaced oppositely disposed locking slots,

guard straps of lesser length than the normal distance between similarly positioned slots in the oppositely disposed flexible chair arms insertable in said slots when the chair arms are flexed toward each other for holding the guard straps under tension when said chair arms are permitted to move toward their original position, and bumper cushion strips detachably secured to the lower ends of said front and rear seat supports.
